CLAIM

The ornamental design for a locking loop receptacle of articulating arm, as shown and described.

DESCRIPTION

FIG. 1 is a front elevation view of a locking loop receptacle of articulating arm;

FIG. 2 is a left side elevation view thereof;

FIG. 3 is a right side elevation view thereof; and,

FIG. 4 is a front, right perspective view thereof.

The broken lines illustrating the articulating arm of FIGS. 1-4 are environment that form no part of the claimed design, while the remaining broken lines in FIGS. 1-4 illustrate portions of the locking loop receptacle of the articulating arm that form no part of the claimed design.
